UNITED STATES PATENT OFFICE.

ORIN PARKER, OF ROCHESTER, NEW YORK.

CARBID-HOLDER FOR ACETYLENE-GAS GENERATORS.

No. 799,257.

Specification of Letters Patent.

Patented Sept. 12, 1905.

Application filed December 13, 1898. Serial No. 699,122.

To all whom it may concern:

Be it known that I, ORIN PARKER, a citizen of the United States, residing at Rochester, New York, have invented an Improved Holder 5 for Generating Acetylene or other Gas, of which the following is a specification, reference being had to the accompanying drawings.

My invention relates to holders for carbid and the like for use in making gas.

10 My improvements are fully described and illustrated in the following specification and the accompanying drawings, the novel features thereof being specified in the claim annexed to the said specification.

15 In the accompanying drawings, representing my improved apparatus for generating acetylene gas, Figure 1 represents one of the carbid boxes or holders. Figs. 2 and 3 are respectively longitudinal and transverse sections of the same, showing the double walls. Figs. 4, 5, and 6 are similar views of a cylindrical carbid-holder.

20 In order to provide a box or holder for the calcic carbid or other solid gas-making substance which shall be impermeable to vapors, but readily permeable to water or other gas-generating liquid, and which at the same time will permit the escape of the gas produced, I employ a double-walled box A, Figs. 1 to 6, 25 of any suitable shape or dimensions, in which the walls of the inner part of the box fit closely to those of the outer part of the box, the air or gases contained or occluded in the narrow space between the walls serving to prevent the entrance of vapors into the holder, while permitting a liquid to penetrate freely or a gas to escape.

25 It will be seen that in my improved holder I take advantage of the well-known law according to which vapors pass but slowly or not at all through thin films of air or gas occluded between two opposing surfaces. My improved holders may be made of any suitable material; but I have found in practice 40 that some metal, such as cast-iron, is cheap, convenient, and durable. They may also be made of thin tin or lead or a suitable alloy, being cheap enough so that under some circumstances they may be thrown away after 45 use. It is preferable to make the inner surfaces of the walls of the outer receptacle B conical or tapering, as shown in Figs. 2 and 5, and the inner box C is then to be made of a corresponding form, leaving the narrow chan-

nel D between B and C, the inner box being 55 also preferably made of a length somewhat less than that of the outer one. It will be observed that the receptacles composing the holder are nested in reverse, with their solid ends outward, so that the only passage into or 60 out of the holder is through the narrow space between the walls. Calcic carbid placed in these improved holders may be subjected to an atmosphere heavily laden with vapor of water or of other liquids without becoming 65 leached, while at the same time the liquid itself will penetrate to the carbid through the thin channel between the walls whenever the holder is placed in a situation where the liquid can have access to it. In this way the gas-mak- 70 ing substance, such as calcic carbid, can be preserved from decomposition although the holder containing it be placed within a gas-generator until water in liquid form actually comes in contact with the box, in which case 75 the acetylene will be gradually developed owing to the comparatively slow infiltration of the liquid through the narrow space between the opposing walls of the box, and the gas will discharge itself through such space. 80

75 In the practical use of my improved holders they are preferably laid on one side, as in Figs. 2 and 5, with the channel horizontal, so that the liquid may obtain access to the interior through the lower portion of the narrow space, 85 while the gas escapes through the upper portion of the space.

80 The liquid may be supplied to the gas-making substance in my improved holders in any suitable or preferred way. Thus in generating acetylene the holders loaded with calcic carbid may be delivered one after the other into a generator containing water, or a series 90 of them may be arranged at different levels in the gas-generating chamber and the water fed 95 into the chamber so as to rise therein gradually, and thus to obtain access in succession to the holders and the carbid therein. Then either of these systems of water-supply may be controlled by the movements of the gas- 100 ometer or other receptacle for storing the gas.

105 By the use of my improved holder the chemical decomposition which results in the evolution of gas takes place gradually and entirely under control as the liquid infiltrates slowly through the narrow channel, while the gas evolved escapes through the upper portions of the channel. It has not been found neces-

sary to secure the inner and outer boxes together, although this may be readily done, as by a suitable catch or a screw. Carbid will remain practically unaffected for a number of 5 days although surrounded by the freshly-generated vapor-laden gas in an acetylene-generator when inclosed in a cast-iron holder of which only the outside of the inner box C has been planed, the inner box being left just as 10 it came from the sand.

I claim—

The herein-described holder for carbid and

the like, consisting of the inner and outer components open at one side and nested in reverse, having a narrow channel between their opposing surfaces, said channel forming the only means of ingress and egress into or from the interior of the holder, as and for the purposes described. 15

ORIN PARKER.
